FOREIGN PATENT DOCUMENTS

CN 306105167 * 10/2020
WO D234533-001 * 1/2024*Primary Examiner* — Selina Sikder(74) *Attorney, Agent, or Firm* — Tucker Ellis LLP(57) **CLAIM**

The ornamental design for a control module, as shown and described.

DESCRIPTION

FIG. 1 is a perspective view of a control module showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The claimed design is indicated by the relatively dark portions in the figures, while the relatively light portions and the broken lines depict portions of the control module that form no part of the claimed design.
